MONOGRAM

Ivan Wolff, New York, N. Y.

Application December 16, 1935, Serial No. 54,635

10 Claims. (Cl. 40—140)

The subject of the present invention is a new and valuable type of monogram, to include two, three or more individually prefabricated initials or letters, and a new form of initial or letter 5 the combining of a plurality of which makes possible the provision of any monogram required for the display therein of the appropriate letters. By a letter, as that word is used herein, there is meant a plate or equivalent element cut 10 out or equivalently shaped to have an outline in agreement with an outline of a letter of the alphabet, that is, a letter peripheral portions of which coincide with and are defined by peripheral portions of such plate.

15 By a monogram there is meant a number of letters so arranged that each of the letters has one or more parts thereof crossing over or merging with one or more parts of each of the immediately adjoining letters.

20 Previously made monograms having a part of one letter crossing over or merging with a part of another have been specially made as complete monograms; for instance, by so sawing or otherwise cutting out various portions 25 from a single sheet of the selected metal or other material as to define certain bounding lines of the letters making up the monogram. In other words, the monogram desired has to be cut to order. Such a monogram is very costly, 30 in view of the large amount of hand labor required; and some considerable time must be allowed for its manufacture.

One of the objects of the present invention is to provide a set of prefabricated letters such that 35 a monogram can be made up of a plurality of selected letters, whatever be the letters selected, practically instantaneously.

Another object is to provide a set of fabricated letters suitable for combination to form 40 a monogram as above, and at the same time a monogram the appearance of which will suggest that different letters are intermerged rather than actually placed so that one merely partially overlaps another.

45 Another object of the invention, nevertheless, is so to shape the letters that one letter will actually partially overlap another in the monogram.

Another object of the invention, however, is 50 so to shape the letters that, although the objects above stated are attained while so shaping the letters that in any monogram each pair of adjoining letters lap one another, the rear face or bottom of the monogram will be substantially uniplanar over its main expanse, and at the

same time the monogram will be of substantially the same thickness over such expanse where the letters are so designed as to have substantially plane and parallel top and bottom face portions.

Another object is to provide a plurality of 5 prefabricated letters so constructed that the new monogram can be assembled from any group of letters selected, with these letters combinable to form a monogram which will, even when the letters have substantially plane and 10 parallel top and bottom face portions, present an unusually massive appearance in comparison with the actual amount of material present.

Another object is to provide a plurality of 15 prefabricated letters so shaped that the new monogram can be assembled from any several letters selected, whether all the letters are different ones, as A, B and C, or two of them are duplicates, as A, B and B, or all three are alike, as C, C and C.

Another object is to provide a plurality of 20 prefabricated letters not only combinable to produce a monogram pursuant to the invention as above, but also thus combinable regardless of the order in which the letters are placed in the 25 monogram. To explain more clearly: Assuming, for example, that the letters to be combined in the monogram are A, B and C, or even A, B, C and D, an object of the invention, and one now believed to be of large importance to make the 30 invention practicable, is so to shape each of the letters that always the same three or four letters can be used to provide a monogram pursuant to the invention, regardless of which one of the six different sequential possibilities of the 35 letters A, B and C to wit, ABC, ACB, BAC, BCA, CAB and CBA, or of which one of the 24 different sequential possibilities of the letters A, B, C and D, be required to give the monogram specially ordered. With the letters thus inter-

changeable, as to placement in the monogram, there is avoided, in the case of a two letter monogram, any need to provide each letter in two different shapes, one a "right" and the other a "left"; and, similarly, to take care of three and 45 four letter monograms, differently shaped "rights", "centers" and "lefts", and differently shaped "rights", "right centers", "left centers" and "lefts", need not be provided. Otherwise stated, it is an object of the invention to provide, for the purpose of obtaining a monogram pursuant to the invention, a set of letters including all the letters of the alphabet, but with all the letters of this set so made that each of the different letters A, B, C, D and so on, is always of 50 55

one shape, whether that letter is the first, the last or the middle letter of the monogram or some other letter of the monogram intermediate its general line of extension, cross-sectionally.

Such cross-sectional shape results from a depressing of the top surface of the letter along one portion of the outline of the letter and from an elevation of the bottom surface of the letter along a portion of its outline opposite to that first-mentioned. These opposite portions of the outline of the letter can be, for example, those two sides of the letter which are marked by the oppositely located bounds of the letter extending heightwise of the outline thereof, where the monogram is to be built up widthwise of the letters, or those two sides of the letter which are marked by the oppositely located bounds of the letter extending widthwise of the outline thereof, where the monogram is to be built up heightwise of the letters. These depressions and elevations are herein referred to broadly as tapers; which tapers if plane are parallel, and which if otherwise shaped, as, for instance, convex, concave, undulating or stepped, are preferably nicely accurate counterparts, so that one on one side of any letter can be matchingly fitted against the one on the other side of any letter. When the letters of a monogram built up according to the invention are closely interfitted at such tapers, not only is the invention most satisfactorily carried out to attain all the objects foregoing, but the securement of such letters to each other or to any suitable support for holding the letters to their appointed locations for presenting the desired monogram, is facilitated, practically regardless of the mode or means employed to attain such securement, and regardless also of the type of the support.

The invention will be more clearly understood from the following description when taken in connection with the accompanying drawings which illustratively show various now favored of the many possible ways of carrying out the invention.

In said drawing, wherein like reference characters refer to like parts:

Fig. 1 is a top plan of one form of monogram according to the invention;

Fig. 2 shows the same in end elevation looking toward the basal edges of the letters;

Fig. 3 is a view similar to Fig. 1, showing the letter I;

Fig. 4 is a view similar to Fig. 2, showing such I in end elevation;

Fig. 5 is a view showing the top face of the letter J;

Fig. 6 is a view similar to Fig. 2, showing such J in end elevation;

Fig. 7 is a view similar to Fig. 1, but showing a different monogram, yet one including the same letters and letters of the same outline as in Fig. 1;

Fig. 8 is a view similar to Fig. 2, showing said monogram of Fig. 7;

Fig. 9 is a view similar to Fig. 1, but showing still another monogram;

Fig. 10 is a view similar to Fig. 2, showing the monogram of Fig. 9;

Fig. 11 is a view similar to Fig. 1, but showing still another monogram;

Fig. 11a is a view similar to Fig. 2, showing the monogram of Fig. 11;

Fig. 12 is an end elevation of such a letter as L looking toward the basal edge thereof, and

illustrating a form of taper shaping not elsewhere shown;

Fig. 13 is a similar elevation of such a letter, showing still a different form of taper shaping;

Fig. 14 is a similar view, showing still a different form of taper shaping;

Fig. 15 is a similar view, showing still a different form of shaping;

Fig. 16 is a view similar to Fig. 3 or 5, but showing the letter X, and such letter of a special form; and

Fig. 17 is a view showing, in vertical section, a mounting frame for a monogram including letters shaped in accordance with Fig. 16, and also showing said letter X, in side elevation, in place in said frame.

Referring first to Figs. 1 and 2, the monogram shown is one made up of the letters B, A and F, arranged in the order stated; these letters being respectively marked 20, 21 and 22. As best shown in Fig. 2, each letter has a descending upper surface or tapered d opposite an ascending lower surface or taper a. These surfaces being parallel, the three letters can be arranged in any of the six sequences required to give any one of the six possible monograms which can be made from these three letters; since in every case the taper a of one letter will fit against the taper d of any adjoining letter. In each such case, the monogram, although of uniform thickness all over its major expanse, and with the major portions of its front and back faces plane and parallel, has a really surprising appearance. It has the appearance, only imperfectly indicated in Fig. 1, that its main upper surfaces are those of really massive parts overlying and downwardly merging into the parts therebelow. This appearance, strikingly attractive, is apparently a characteristic of any possible embodiment of the invention, even when the letters are fabricated of comparatively thin stock.

The design of block letters shown in Fig. 1, although the same general design is used throughout the drawing, is selected for simplicity of illustration merely. Any design of letters, either with heightwise sides inclined or otherwise shaped, or with widthwise sides inclined or otherwise shaped, and whether more elaborate block letters or rather grotesquely distorted ones, or script, Gothic or other letters, can be employed. Referring to the plain block letters shown throughout the drawing, these can be varied not only as just indicated but otherwise; for instance, they can be considerably attenuated heightwise or widthwise thereof, as can, of course, any other design of letters adopted. Nor need the top and bottom faces of the letters be plane, or plane and parallel. Also, although in the forms illustrated, the tapers extend widthwise of the letters, they can extend otherwise, as lengthwise of the letters. Again, while in the forms illustrated the descending tapers d are leftwardly directed and the ascending tapers a are rightwardly directed, such arrangement can be reversed, in any form of the invention where these tapers are at opposite locations across the face of the letter widthwise thereof.

Referring to Figs. 3 and 4, a letter I is shown at 23 which could be used with the set of letters including the letters B, A and F of Fig. 1. Note that the ascending taper a and the descending taper d of this I are given the same angle as the tapers a and d of the three letters of Fig. 1, 75

but that these tapers of I, in view of the reduced width of the I, are less extensive widthwise of the letter than the same tapers of the letters B, A and F and those letters as wide as B, A and F.

Referring to Figs. 5 and 6, a letter J is shown at 24 which could be used with the set of letters just referred to. Note that here also the same angle is employed for the tapers *a* and *d* of J. Since this J is shown as having a width which is less than that of the other letters except I, but a width greater than that of I, here again we have a distinctly different cross-sectional result.

Referring to Figs. 7 and 8, the same letters here appear as are shown in Figs. 1 and 2. But a decidedly different decorative effect is obtained. The tapers corresponding to the tapers *a* and *d* of Figs. 1 and 2, instead of extending over substantially 50% of the face of the letter as in Figs. 1 and 2, extend over only about 25% of the face of the letter. The end elevations of the letters B, A and F are indicated in Fig. 8 at 25, 26 and 27, respectively.

Referring to Figs. 9 and 10, in this monogram there is employed a letter B which is the same B as that shown in Figs. 1 and 7 except that here it is narrower in width, being as wide as the J of Fig. 5. Employing this B in combination with the letters I and J of Figs. 3 and 5, and keeping to the same angle for the tapers of these letters as employed in Fig. 7 for the wider letters there shown, another pleasing type of monogram is obtained, that seen in Fig. 9. The end elevations of the letters J, B and I of Fig. 9 are indicated in Fig. 10 at 28, 29 and 30, respectively.

Thus even from plain stock having flat parallel faces, and even with the same block letters, a large number of variations in appearance of the monogram can be obtained. These variations follow from the angle of taper and/or the degree in which the taper extends laterally over the face of the letter and/or the thickness of the stock. It will be noted that the letters of Figs. 1 and 7 and the letters J and B of Fig. 9, since the top and bottom faces of these letters are plane and parallel, and their tapers are also plane and parallel, are all rhomboidal in end elevation.

Important variations of appearance in the completed monogram can be obtained by shaping the upper faces of the letters, beyond their descending tapers, in any way or ways desired.

As one illustration, reference is made to Figs. 11 and 11a; where, for example, the letters C, R and K are shown at 30', 31 and 32, respectively, and where, with the bottom faces of such letters plane, the top faces thereof are arcuately convex widthwise of the letter. As here shown, also, the descending tapers on the letters are the parts of such convexities at the left hand sides of the letters, and the ascending tapers on the letters, one of which, that for the letter K, is marked *a'* in Fig. 11a, are concavities forming counterparts of said descending tapers.

Even, for instance, with the top and bottom faces of the letters plane and parallel, other decorative results can be obtained by using other types of ascending and descending tapers than plane ones, but so shaped that one on one letter will matchingly engage the other on an adjoining letter. Some of the possibilities in this regard are illustrated in Figs. 12, 13, 14 and 15; the tapers here shown being marked 12a and 12d

in Fig. 12, 13a and 13d in Fig. 13, 14a and 14d in Fig. 14 and 15a and 15d in Fig. 15. It will be noted that the tapers of Fig. 14 are widthwise curvilinearly undulant, while the tapers of Fig. 15 are stepped, and angularly stepped, at a plurality of points across their widths.

As already indicated, any suitable way of permanently establishing the new monogram can be adopted; that is to say, the present invention is not concerned especially with the means employed to establish the monogram either by anchoring the component letters together or by securing such letters to a suitable support. Such letters could be secured together, of course, by riveting them together at their lapped portions, by soldering or in any way desired. Or they could be secured together by anchoring them in place on a suitable support in such manner that as the result of such anchoring the lapped portions of the letters will be held against shifting from such lapping. If the monogram is to be a fob or pendant of any kind, it will probably be better to secure the letters directly together by way of their lapped portions, in some suitable way. If, on the other hand, the monogram is to be mounted on a piercable support, as the leather covering of a purse, bag or the like, or in a rigid frame of metal, the letters need not be joined at their lapped portions. As to leather bags or the like, the monogram can be fixed thereon by mounting the individual letters, when lapped pursuant to the invention, by means of flexible prongs soldered or otherwise secured to the bottom faces of the letters in ways well known in the art. Any such prong or equivalent is attached to a letter, of course, at a point such that there will be no interference with the revised lapping of that letter by an adjoining one. In this connection, see Figs. 9 and 10, and note the pair of prongs, marked *p* and *p'*, on the letter I. Where the monogram is to be established on a support by mounting the letters in a frame of metal or the like, any one of the various expedients well known in the art for mounting merely a line of individually completely visible letters in such a frame can be adopted, but always, of course, to have the frame seize other edge portions of the letters than those carrying the tapers. Referring now to Figs. 16 and 17, one such expedient is illustrated

in connection with a rectangular frame 33, shown only in Fig. 17, and the letter X, marked 34 in Figs. 16 and 17, mounted in such frame. This frame, along its top and bottom members, at the underside of the former and at the upper side of the latter, carries a beadlike straight rib 35 and across the portions of the T at its widthwise sides are grooves 36. The letters to make up the monogram are snapped into the frame by pressure applied at their backs, that is, in the direction of the arrow 37 in Fig. 17; the frame giving a trifle, or the letter springing elastically out of the flat, or both these actions occurring, at the instant the grooves of a letter snap beyond the frame ribs and lock about the same. As will be understood, the letters are snapped one by one into the frame in the order corresponding to that in which they are to have mutually lapping portions in the monogram being set into the frame.

I claim:

1. A plurality of elements each having an outline in agreement with an outline of a different letter of the alphabet, all said elements being made so as to be of substantially the same thick-

- ness at their median portions, each of said elements having two oppositely located portions of reduced thickness each including a part of the periphery of the letter, one of such reduced portions having a back face forming substantially a smooth continuation of the back face of the median portion of the element and the other of said reduced portions having a front face forming a substantially smooth continuation of the front face of said median portion.
2. A plurality of elements each having an outline in agreement with an outline of a different letter of the alphabet, all said elements being made so as to be substantially the same thickness, each of said elements having two oppositely located reduced portions, one of said reduced portions having a face at the back of the element and the other of said reduced portions having a face at the front of the element, said faces being substantially parallel and defining between them the maximum thickness of the element.
3. A plurality of elements each having an outline in agreement with an outline of a different letter of the alphabet, all said elements being made so as to be of substantially the same thickness, each of said elements being shaped across the same to have top and bottom surface elements both below the top and above the bottom of the element, these top and bottom surface elements being along opposite sides of the element.
4. A plurality of elements each having an outline in agreement with an outline of a different letter of the alphabet, all said elements being made so as to be of substantially the same thickness, each of said elements being thinned away at diagonally opposite portions, these thinned away portions being shaped for the fitting of one such portion on one element against one such portion on another element to allow partial lapping of a plurality of the elements to give a monogram effect.
5. A plurality of elements each having an outline in agreement with an outline of a different letter of the alphabet, all said elements being made so as to be of substantially the same thickness, each of said elements being shaped to a diminished thickness along each of two lines at opposite sides of the element, each of such diminished portions having a substantially plane surface, said surfaces being parallel, one of said surfaces coinciding with the top of the element and the other coinciding with the bottom of the element.
6. A plurality of elements each having an outline in agreement with an outline of a different letter of the alphabet, all said elements being made so as to be of substantially the same thickness, each of said elements being shaped to have oppositely located portions of reduced thickness, the overlying surface of one of said portions being a counterpart of the underlying surface of the other portion.

7. A plurality of elements each having an outline in agreement with an outline of a different letter of the alphabet, all said elements being made so as to be of substantially the same thickness, each of said elements being shaped to have oppositely located portions of reduced thickness, the overlying surface of one of said portions being a counterpart of the underlying surface of the other portion, said overlying surface being below the topmost point of the top face of the element and said underlying surface being above the bottommost point of the bottom face of the element.

8. A plurality of elements each having an outline in agreement with an outline of a different letter of the alphabet, all said elements being made so as to be of substantially the same thickness, each of said elements being shaped to have diagonally disposed and oppositely directed portions of less thickness, said portions being so shaped that an upper surface of one such portion on one element will fit against an undersurface of the other such portion on another element thereby to permit the elements to be partially lapped to obtain a monogram effect while maintaining the sum of the thicknesses of said two elements where thus lapped substantially equal to the thickness first-mentioned.

9. A plurality of elements each having an outline in agreement with an outline of a different letter of the alphabet, all said elements being made so as to be of substantially the same thickness, each of said elements being reduced in thickness along opposite sides, the top face of each element being lowered at one of these thickness reductions and the bottom face of each element being raised at the other of these thickness reductions, such raised and lowered surface elements on each element being matchingly shaped so that one of such surface elements of one element may be fitted against the other of such surface elements of any other element, to cause partial lapping of such elements regardless of which element is placed ahead of another.

10. A monogram including a plurality of elements each individually prefabricated to have an outline in agreement with an outline of a letter of the alphabet, each of said elements being thinned along oppositely located sides, one of such thinnings being at the upper face of the element and the other at the bottom face of the element, the two elements of each pair of said elements immediately adjoining being lapped at their thinned portions; a thinning at the upper face of any element being shaped to fit against a thinning at the under surface of any other element whereby in a monogram made up of any of said elements the sum of the thicknesses of any pair of lapped element portions is substantially equal to the thickness of an element beyond such portions.

IVAN WOLFF.
